ABRASIVE WHEEL AND MOUNTING

Hugo W. H. Beth, Worcester, Mass., assignor to
Norton Company, Worcester, Mass., a corpora-
tion of Massachusetts

Application January 4, 1936, Serial No. 57,621

13 Claims. (Cl. 51—209)

The invention relates to abrasive wheels and mountings therefor.

One object of the invention is to provide an abrasive wheel and mounting adapted to withstand a high degree of heat during grinding. Another object of the invention is to provide an abrasive wheel and mounting with provision for the differential between the coefficient of expansion of the wheel substance and the mounting substance. Another object of the invention is to provide a stronger union between the abrasive wheel and mounting under varied conditions of practical use. Another object of the invention is to provide an improved mounting plate for an abrasive wheel. Another object of the invention is to provide a construction for an abrasive wheel and mounting facilitating assembly. Another object of the invention is to provide an integral side face grinding wheel united to a metal backing plate with a tough and strong union adapted to withstand a high degree of heat. Other objects will be in part obvious or in part pointed out hereinafter.

The invention accordingly consists in the features of construction, combinations of elements and arrangements of parts as will be exemplified in the structure to be hereinafter described, and the scope of the application of which will be indicated in the following claims.

In the accompanying drawing in which is shown one of the various possible embodiments of the mechanical features of this invention,

Figure 1 is a plan view of a mounting plate constructed in accordance with the invention;

Figure 2 is a cross sectional view taken on the line 2—2 of Figure 1 of the mounting plate of Figure 1 with an abrasive wheel attached thereto.

As conducive to a clearer understanding of the present invention, it is noted that there are particular grinding purposes for which a wheel grinding on a radial surface, which may be annular or otherwise, is preferred. It is often a requirement in such a grinding operation that there shall be nothing projecting beyond the plane of the grinding face in the direction away from the supporting spindle or other supporting means. To mount such grinding wheels there have been hitherto proposed both soft and hard rubber as a cement uniting the wheel to a backing plate which can be readily attached to a spindle. By soft rubber is meant a rubber vulcanized with a relatively small amount of sulphur which rubber is reasonably resilient. By hard rubber is meant that substance sometimes called ebonite which is vulcanized with a larger amount of sulphur,

usually 20% or more, and which is relatively rigid. Hard rubber has an advantage over soft rubber in that it has greater tensile strength, and no cement however great its properties of adhesion can be any stronger than the coherence of its particles to each other. Hard rubber has the further advantage that it is less susceptible to thermal effects, and sometimes wheels such as herein mentioned are caused to do so much work that overheating occurs, therefore making the resistance to heat of the cement a factor of importance. On the other hand, as a steel or iron backing plate is usually used on account of its strength and other desirable qualities, and as the coefficient of expansion of steel or iron is different from that of many grinding wheels, the soft rubber has had the advantage that, being resilient, differences of coefficient of expansion become immaterial while hard rubber, having no such resilient or plastic qualities, or to a lesser degree, there has been experienced rupturing of the cement in cases where the diameter of the wheel was large.

Referring now to the illustrated embodiment of the invention and more particularly to Figure 2, I provide a grinding wheel 10 shown as a cylindrical annulus, the radial face 11 being a grinding face. This grinding wheel 10 is to be secured to a spindle 12 having an integral disk-like flange 13 with a plurality of tapped holes 14. The spindle 12 may be mounted in any suitable bearings and rotated in any suitable manner and may be part of a complete machine, not shown. There is no particular significance to the orientation of the axis of the spindle 12 in the present drawing, and actually the spindle 12 might be inverted from the position shown, or might be horizontal, or might be positioned in any other position desired.

I provide a metal backing plate 15 whose area is preferably the same as the area of the outside circle of the annular grinding wheel 10. This plate 15 is desirably a steel plate, since steel provides the desired strength, is relatively inexpensive and may be readily cut to provide the special features now to be described. By means of a suitable die or in any other desired manner I cut a series of arcuate slots 16 in the plate 15. These slots 16 are located around a circle, are discontinuous from each other, and leave an appreciable arc of metal 17 between each adjacent slot. In another circle, and as shown in a circle of lesser radius, I provide a second series of arcuate slots 18, each subtending substantially the same arc as each of the slots 16, and each pair leav-

ing a substantial arc of metal 19 between them. As the circle of the slots 18 is spaced from the circle of the slots 16 by a substantial distance, it will be seen that the plate is continuous from the 5 central hole 20 therein to the periphery along, however, irregular lines. Preferably I provide radial slots 21 from the periphery of the plate 15 to the slots 16 and preferably meeting the slots 16 at the mid points thereof. The plate 15 also 10 has a plurality of screw holes 22 which may be countersunk as shown and which are arranged to match the tapped holes 14. The central hole 20 may be omitted if desired, but it is provided if the flange 13 has a centering projection 23.

15 Any portion of the backing plate or disk 15 which is substantially bounded by any of the slots specified can be moved a limited distance in any direction parallel to the plane of the faces of the disk 15. There is a certain amount of give to 20 hard rubber so that, for areas whose greatest linear dimension does not exceed a certain size, a metal plate and a grinding composition secured together by hard rubber presents no rupturing possibilities over a given range of temperature, 25 whereas, in larger sizes, the same grinding composition and the same type of plate secured by the same hard rubber cement might separate by cracking of the cement upon cooling of the article from the vulcanizing temperature, owing to 30 the differential in coefficients of expansion, and on account of inability of the rubber to conform itself to relative movement of a portion of the plate and a portion of the composition over such a great linear distance.

35 It will be seen that a plate made as described presents definite areas marked 25 which are almost, if not quite, islands with respect to the central body portion 26 of the plate, the joining metal 27 being narrow and therefore flexible. 40 As the greatest dimension of the areas 25 is still less than the limiting dimensions so far as rupturing is concerned, when the invention is embodied in the form of a vitrified grinding wheel and a steel plate not greater than 24 inches in diameter, danger of rupturing on account of differences of coefficient of expansion is avoided even when using a hard rubber cement. For wheels and plates of larger diameter than that just 45 specified, a greater number of arcuate slots 16 and a greater number of slots 21 may be provided. Not only may the islands 25 move with respect to the body portion 26, but it is noted that due to the disposition of the slots, motion in a radial line is relatively freer than motion in a circumferential direction, and it is the relative radial 50 stresses that have caused the greatest difficulty.

Having provided an annular wheel 10 and a steel backing plate 15 as described, I secure them together with hard rubber cement 30 in the following manner. Sand blasting one side of the plate 15, I place a thin sheet (for example $\frac{1}{8}$ of a 55 inch thick) of vulcanized hard rubber composition, being milled rubber containing 20% or more of sulphur, upon the plate 15, and then place the grinding wheel 10 in matching relationship upon the rubber, and secure the parts together with ordinary screw clamps. I prefer to use a number of clamps equal to the islands 25 60 so that each one of them will be in intimate contact with the rubber. I prefer to locate the clamps so that they cross the slots 21 or else provide double the number of clamps so that each portion 25 will be secured at both edges, and it 65 is even desirable to provide treble the number of 70

clamps that there are portions 25 so that each portion may be clamped in three places, on each edge and in the middle. I now place the clamped plate and wheel with the unvulcanized hard rubber composition between them in the vulcanizing oven and vulcanize at a temperature and for a length of time which is well understood by those cognizant of the manufacture of hard rubber, for example fourteen hours at 160° C. 10

The wheel and plate are now securely fastened together and in the cooling of the combined article from vulcanizing temperature cracks do not appear on account of the features of construction already explained. The plate may be readily secured by means of screws 31 to the flange 13, 15 and may as readily be detached therefrom. It will be understood that many other cements may be used besides the ordinary hard rubber composition comprising rubber and sulphur, and the advantageous features of the invention are 20 achieved with any cement which provides a strong union. Using hard rubber, or hard rubber modified, or any other cement having high heat resistant properties, such as phenolic resins or other artificial resins, the grinding wheel 10 may 25 be subjected to such severe operations that great heat is generated without in any way disrupting the union between plate and wheel or endangering the plate. Furthermore if the wheel 10 does 30 break, its portions are held to the backing plate 15 so that they will not fly out.

While vitrified wheels may be particularly mentioned, the invention is likewise applicable to other types of grinding wheels, such as silicate bonded grinding wheels, cement bonded grinding 35 wheels, rubber, shellac, and artificial resin bonded grinding wheels, and any abrasive material whatsoever may be used to form the grinding wheel.

It will thus be seen that there has been provided by this invention an article in which the various objects hereinabove set forth together with many thoroughly practical advantages are successfully achieved. As many possible embodiments may be made of the above invention and as many changes might be made in the embodiment above set forth, it is to be understood that all matter hereinbefore set forth, or illustrated in the accompanying drawing, is to be interpreted as illustrative and not in a limiting sense. 40

I claim:

1. A combination grinding wheel and backing plate comprising an abrasive annulus, a metal plate secured thereto, said plate having arcuate slots therein, and a cement joining the annulus to the plate. 50
2. A backing plate for grinding wheels having arcuate slots in a circle. 55
3. A backing plate for grinding wheels having arcuate slots in a plurality of concentric circles. 60
4. A backing plate for grinding wheels having radial slots. 65
5. A backing plate for grinding wheels having arcuate slots in two concentric circles in staggered relation. 70
6. A backing plate for grinding wheels having radial slots and arcuate slots in a circle. 75
7. A backing plate for grinding wheels having arcuate slots in two concentric circles and radial slots. 80
8. A plate as claimed in claim 2 having a grinding wheel cemented thereto with a tough cement. 85
9. A plate as claimed in claim 3 having a grinding wheel cemented thereto with a tough cement. 90
10. A plate as claimed in claim 4 having a 75

grinding wheel cemented thereto with a tough cement.

11. A plate as claimed in claim 5 having a grinding wheel cemented thereto with a tough cement.

12. A plate as claimed in claim 6 having a

grinding wheel cemented thereto with a tough cement.

13. A plate as claimed in claim 7 having a grinding wheel cemented thereto with a tough cement.
